HAIR THINNING CLIPPER

Bogoa Strezzoff, Minneapolis, Minn.

Application January 9, 1941, Serial No. 373,735

6 Claims. (Cl. 30—208)

This invention relates to clipper constructions and more particularly to a clipper construction which is particularly adapted for use with an interchangeable set of blades for thinning hair.

Shears having a straight blade and a toothed blade are now in use. However, these shears have, after a short period of use, become worn due to the fact that the toothed portions of one blade dig into the edge of the straight blade forming notches therein. This is caused by the shearing action of the two blades which are bowed slightly in order to secure effective cutting throughout the length of the blades. When the notches become worn in the straight blade they affect the cutting efficiency of the shears and frequently cause hairs to be caught in the notches and either cut improperly or not at all. When they catch and do not cut they, of course, pull the hair causing physical discomfort.

One of the objects of my invention is to provide a simple form of clipper construction with a set of blades for hair thinning which overcomes the objections present in hair thinning scissors.

Another object of the invention is to provide a unit of a pair of movable blades which are slidably interconnected and which are arranged for simple and quick attachment to and detachment from a clippers unit.

These and other objects and advantages of the invention will more fully appear from the following description made in connection with the accompanying drawing, wherein like reference characters refer to the same parts throughout the views, and, in which:

Fig. 1 is a view partially in vertical section of hair clippers with my invention applied thereto;

Fig. 2 is a plan view with the cover portion broken away; and

Fig. 3 is a section taken approximately on the line 3—3 of Fig. 2.

In the drawing there is shown a relatively stationary handle member 4 having a housing 5 and a plate portion 6 attached thereto. A relatively movable handle or blade operating arm 7 is pivotally connected to the plate 6 by means of a stud 8 which passes through a hub portion 9 on the movable arm 7, through the plate 6 and is adapted to be threaded into a lower stationary clipper blade 10. The stud 8 extends through a cover cap 11 and may be provided with a spring washer 12 to keep the parts together under compression.

A pair of pins 13 extend downwardly from the plate 6 and into apertures 14 in the lower blade 10

10 to prevent said blade from moving about the stud 8.

An upper movable blade 15 is slidably supported upon the lower blade 10 and said upper blade is provided with a pair of guide grooves 16 which receive upwardly extending posts 17 on the lower clipper blade 10. An additional guide member 18 rides in a channel or slot 19, and the member 18 is retained in position by a screw 20 which extends upwardly through the lower blade and into the slot 18 in the upper blade. The upper blade 15 is reciprocated by an arm 21 which is connected to the hub 9 on the movable handle or operating arm 7.

15 The lower clipper blade 10 is provided with a plurality of outwardly extending teeth 22 which have rounded and somewhat pointed ends, as shown best in Fig. 2, and said teeth 22 are considerably wider and more widely spaced than the teeth of a conventional hair clipper. The teeth 22 are flat on top and their edges 23 are substantially square to provide shear portions for cooperating with other teeth on the upper blade to be described below.

20 The upper blade 15 has a plurality of arms 24 extending outwardly therefrom parallel to the teeth 22 on the lower blade 10, and, as best shown in Fig. 2, they terminate at the bases of the somewhat pointed ends of the teeth 22. The arms 24 carry a plurality of relatively small hair engaging teeth 25 in whose outer ends are formed generally V-shaped notches 26. The small hair engaging teeth 25 when moved with the blade 15 with which they are attached describe a recti-

25 linear movement and pass over the upper faces of the lower teeth 22 in closely associated relation thereto so that any hair cut in the notches 26 on the teeth 25 will be sheared off by the edges 23 of the lower teeth 22. Of course, the edges of 30 the notches 26 may also be sharpened to perform a cutting action if desired, but this is not absolutely necessary.

35 When clippers embodying my invention are used they are inserted in the hair with the blades 45 in the position shown in Fig. 2 so that groups of hairs will lie in the spaces between the lower blade teeth 22. It should be noted that the upper blade arms 24 and their relatively small hair engaging teeth 25 overlie certain of the lower blade teeth 22 to permit the hair to pass freely 50 between the latter teeth. The operating arm 7 is then pressed toward the relatively stationary handle or arm 4 to move the slideable upper blade 15 relative to the stationary lower blade whereupon the hair engaging teeth 25 will move

across the spaces between the lower blade teeth 22 and a small quantity of hair will be caught by each of the notches 26 in said teeth 25. At the end of the stroke the notches 26 will have passed slightly beyond the edges 23 of the lower teeth 22 causing that hair caught in the notches to be sheared off. The hair which is not caught by the notches 26 in the small teeth 25 will fall between said teeth and, of course, will not be cut. The arms 24 do not cross the space between the lower teeth 22 and for that reason none of the uncut hair is caught between said arms and said teeth 22. When the clippers are released the spring 1a in the housing 5 will swing the arms apart and cause the upper blade 15 to return to the position shown in Fig. 2, thus releasing the uncut hair from the spaces between the teeth 22.

It should be noted that the hair thinning blade unit can be quickly removed from the remainder of the clippers by reverse rotation of the stud 8, and as soon as said stud has been taken out of the lower blade 10, said blade will slip over the pins 13 on the plate 6 and the entire blade unit is removed.

From the foregoing description it will be seen that I have provided an improved clipper construction which permits the attachment of a pair of hair thinning blades to clippers and also provides a hair thinning apparatus which does not cause wear of the hair catching teeth on the cooperating cutting member since there is a controlled movement of one blade relative to the other in true parallel planes or in substantially the same parallel plane. This overcomes the disadvantages found in hair cutting shears.

The device is relatively simply constructed and can be used by a barber who is familiar with the use of ordinary hair clippers.

It will, of course, be understood that various changes may be made in the form, details, arrangement and proportions of the various parts without departing from the scope of my invention.

What is claimed is:

1. In a hair clipper, a first blade having a plurality of spaced teeth extending outwardly from an edge thereof, side portions of said teeth constituting shear members, a second blade slidable relative to said first blade and having arms extending outwardly therefrom adjacent the teeth of said first blade, said arms, in one position of said second blade relative to said first blade, overlying the teeth of said first blade and in another position of said blades relative to each other, said arms lying between teeth of said first blade, said arms having relatively small spaced hair engaging members movable across the space between the teeth of said first blade and adapted to engage small quantities of hair and to cut said hair in cooperation with the shearing members of the teeth of said first blade, and means for reciprocating said blades relative to each other.

2. In a hair clipper, a first blade having a plurality of spaced teeth extending outwardly from an edge thereof, a second blade slidable relative to said first blade and having relatively narrow arms extending outwardly therefrom

adjacent the teeth of said first blade, a plurality of relatively small hair engaging teeth extending from said second blade arms at an angle to the teeth of said first blade, said relatively small hair engaging teeth being movable past edges of said first blade teeth in closely associated relationship thereto, and means for actuating one of said blades reciprocally relative to the other of said blades.

3. In a hair clipper, a first blade having a plurality of spaced teeth extending outwardly from an edge thereof, a second blade slidable relative to said first blade and having relatively narrow arms extending outwardly therefrom adjacent the teeth of said first blade, a plurality of relatively small hair engaging teeth extending laterally from the arms of said second blade and approximately transversely relative to the teeth of said first blade, said hair engaging teeth having hair receiving notches in their ends, said arms and hair engaging teeth in one position of said blades, overlying the teeth of said first blade, and said blades being relatively movable to bring the notched portions of said hair engaging teeth past an edge of a next adjacent tooth of said first blade.

4. In a hair clipper, a first blade having a plurality of spaced teeth extending outwardly from an edge thereof, a second blade slidable relative to said first blade and having a plurality of arms extending outwardly therefrom adjacent the teeth of said first blade, a plurality of relatively small hair engaging teeth extending from said second blade arms generally transversely with respect to the teeth of said first blade, the width of said arms plus the outward extension of said hair engaging teeth being substantially no greater than the width of said first blade, said blades in one position having the arms and hair engaging teeth of said second blade overlying the teeth of said first blade, and said blades being movable to bring the said hair engaging teeth across the spaces between said first blade teeth, and means for reciprocating said teeth relative to each other.

5. In a hair clipper, a first blade and a second blade connected together for relative sliding movement, cooperative hair thinning elements on said blades operative upon relative movement between said blades, a relatively movable arm unit, a stud extending through a portion of said arm unit and threaded into one of said blades to draw said blade and arm unit into close association, means connecting said movable arm unit and its connected blade to prevent movement of said blade about said stud, and a drive connection between said movable arm unit and the other of said blades.

6. In a hair clipper, a pair of relatively movable blades having cooperating hair cutting means thereon, guide means causing said blades to move rectilinear relative to each other, a blade operating arm unit, a threaded connection between said arm unit and one of said blades, a pin and socket connection between said operating arm unit and said threaded connection between said blade, and a drive connection between said operating arm unit and the other of said blades.

BOGOIA STREZOFF.
